SIGNALING SYSTEM

James L. Finch, Patchogue, N. Y., assignor to
 Radio Corporation of America, a corporation of
 Delaware

Application February 4, 1938, Serial No. 188,700

7 Claims. (Cl. 178—66)

This application concerns a new and improved signaling system adapted for producing wave energy, amplifying and keying the same and transmitting the same. The invention is also applicable to the production of wave energy, phase modulation of the wave energy, amplification and keying of the phase modulated wave energy and transmission of the same. A feature of the invention is the use of a non-linear resistance 5 shunting the keying tube to protect the same from destruction in the case of failure of the circuits or improper operation thereof in any respect, which results in excessive voltages being placed on the keying tube.

10 In describing my invention in detail reference will be made to the drawing wherein the single figure illustrates the main features of my invention.

15 In the drawing, wave energy for signaling purposes is produced by an oscillator comprising an electron discharge device 10 having its electrodes connected in oscillation producing circuits including a piezo-electric crystal 12. The tube 10 is preferably of the screen grid type so that 20 undesired coupling is prevented and, as will be noted, this oscillator relies solely on the crystal for tuning the same to the desired frequency. Obviously, this results in oscillations of substantially constant frequency being developed at all 25 times. The oscillations produced in 10 are supplied to an amplifier tube 16 which has its control grid 18 coupled to the anode of 10. The amplifier 16 may simultaneously multiply the frequency of the produced oscillations and its 30 output circuit may be tuned to the fundamental or a harmonic of the fundamental to which the wave energy is to be multiplied.

35 Wave energy is supplied from the output circuit of amplifier 16 to an additional amplifier 20 having its control grid 22 coupled to the anode circuit of 16. The amplifier 20 may also multiply the frequency of the waves supplied thereto, in which case its anode circuit 30 may be tuned to the frequency supplied from the output of 16 or to a multiple thereof. The tuned circuit 30 is 40 connected between the anode 21 and a point of high potential on a source of potential not shown. This amplifier 20 also serves as the keyed stage, as will be described hereinafter. A third amplifier 45 comprising an electron discharge device 26, has its control grid 28 coupled to the tuned circuit 30 to derive therefrom voltages of the frequency to which 30 is tuned. These voltages are amplified in 26, appear in tuned circuit 32, and are 50 impressed on the input of an additional push-pull

amplifier comprising tubes 34 and 36. The output electrodes of tubes 34 and 36 are connected by a tuned tank circuit 38 which supplies the amplified wave energy to an additional and final amplifier comprising tubes 40 and 42. The output of tubes 40 and 42 appears in the tuned circuit 44 and is supplied therefrom to a coupled inductance 46 and from 46 to any utilization circuit.

5 The electrode energizing circuits are, to some extent, conventional and are not of the present invention except as otherwise described in detail below.

10 In order to regulate voltages, non-linear resistances, such as Thyrite, are used in the energizing circuits, as for example, in the cathode return of the tubes 40 and 42 and in shunt to the source of potential not shown. The drop of potential through these non-linear resistances does 15 not increase as rapidly as change of current therethrough increases and therefore more constant voltages are available for the electrodes in the tubes of the circuits.

15 The oscillator 10, if desired, may be phase modulated by signals applied to a transformer 25 50, the secondary of which is between the cathode 52 of oscillator 10 and point of low potential. This cathode is swung relative to ground in accordance with the potentials applied at 50 and the oscillations produced in 10 are thereby phase 20 modulated due to the changes in the cathode to grid current, impedances, reactance, etc. The manner in which this phase modulation is accomplished has been set forth more in detail in Goldstine United States Patents #2,067,081, dated January 5, 1937; #2,067,082, dated January 5, 1937, and Patent 2,111,587, dated March 22, 1938. If the potentials applied at 50 are intelligible signals the oscillations produced in 10 are modulated in accordance with said signals. 40 When telegraphy signals are to be transmitted in this particular embodiment the signals at 50 may be of a single frequency so that the generated oscillations in 10 are wobbled in phase around a point of substantially fixed phase. This 45 wobbling of the phase or frequency of the produced oscillations enhances the transmission effectiveness thereof by obtaining the benefits of frequency diversity in transmission.

50 The oscillations generated in 10, wobbled in phase, as described above or unmodified by waves at 50 are keyed by a keying system of the absorber type comprising a tube 60 having its grid 62 coupled to any source of keying potentials as shown and its anode 64 connected with the anode 55

21 of amplifier tube 20 through the inductance of tuned circuit 30. By this connection the current and voltage supplied by the line 68 is shared by tubes 20 and 60. When 62 is biased more positive or less negative relative to the cathode 66 of tube 60 the tube draws more current to thereby rob tube 20 of current and voltages and the wave amplitude supplied by 20 to 28 is reduced. When the grid 62 of tube 60 is made more negative or 10 less positive relative to the cathode 66, tube 60 draws less current and tube 20 gets more voltage and current in its anode circuit and the amplitude of the wave energy supplied from circuit 30 to tube 28 goes up. In this manner keying is 15 accomplished.

15 To obtain potentials intermediate between those of terminals 68 and 70 for various circuits of this transmitter a potentiometer is connected between 68 and 70 and connections made along 20 this potentiometer to obtain these voltages. During keying operations the current drawn from these connections varies widely and tends to cause the potentials to depart from the desired values. This tendency is very greatly reduced by 25 employing in the potentiometer non-linear resistances such as Thyrite so that the voltage drop grows at a rate less than linear relative to increase in current drawn. This causes the voltage to be more constant on all stages during operation and in particular on the oscillator stage, 30 thereby improving stability of operation.

The keying tube 60 has its anode to cathode impedance shunted by a non-linear resistance 80 such as Thyrite to prevent destruction of this 35 tube in the event of failure of the equipment such as results for example, in over-loading 60 by excessive voltage from 68 and 70. Interruption of the plate circuit of tube 20 is an example of failure or improper operation which might 40 cause overload on 60. Likewise, accidental removal of several of the stages would unload the source of direct current to an extent such that excessive voltages appear across the anode and cathode of 60. The non-linear resistance 80 is 45 of a value and impedance such that it shorts-circuits excessive voltages and dissipates the energy of the current produced thereby to thereby protect tube 60.

The non-linear resistances referred to hereinbefore are of a nature such that the potential 50 drop thereacross does not increase linearly with respect to current increase therethrough. That is, the resistance value of the material used decreases faster than linear with respect to voltage 55 increases so that current therethrough increases at a rate greater than linear with respect to the voltage increases. A material of this nature having the trade name Thyrite has been described by K. B. McEachron in his Patent No. 1,822,742, dated September 8, 1931.

60 I claim:

1. In a signaling system, an electron discharge device having electrodes connected with a common source of potential, means for maintaining the voltages applied to said electrodes by said 65 source of potential of substantial constant value comprising non-linear resistances shunting said source, means for varying the impedance of said discharge device at signal frequency and means 70 for protecting said device against excessive voltages comprising a non-linear resistance shunting the electrodes of said device to dissipate excessive energy applied thereto.

75 2. In a telegraph system a keyed stage including an electron discharge device having electrodes

and a keying stage comprising an electron discharge device having electrodes connected with electrodes in said keyed stage and with a common source of potential, means for varying the impedance of said keying stage discharge device at signal frequency and a non-linear resistance shunting the electrodes of said keying stage device to bypass excessive voltage applied thereto. 5

3. In a telegraph system, an electron discharge device having a plurality of electrodes, means 10 for impressing wave energy on one of said electrodes, a utilization circuit coupled with other of said electrodes, a source of direct current voltage, a keying tube having a controlling electrode connected with a source of keying potentials 15 and having electrodes coupled in shunt to electrodes of said first named device and to said source of voltage whereby voltage supplied to the electrodes of said first named device is controlled in accordance with the keying potentials on the 20 controlling electrode of said second named tube, and means for protecting said second named tube from excessive voltages comprising a non-linear resistance in shunt to a pair of electrodes thereof.

4. In a telegraph system, an electron discharge 25 device having input electrodes and output electrodes, means for impressing phase wobbled oscillations on said input electrodes, a utilization circuit coupled with said output electrodes, a source of direct current voltage, a keying tube 30 having a controlling electrode connected with a source of keying potentials and output electrodes coupled in shunt to the output electrodes of said first named device and to said source of voltage whereby voltage supplied to said first named device is controlled in accordance with the keying 35 potentials on the input electrodes of said second named tube, and means for protecting said second named tube from excessive voltages comprising a non-linear resistance in shunt to the 40 output electrodes thereof.

5. In a telegraph system, a source of oscillations of substantially constant frequency, an amplifier tube having input electrodes coupled with said source of oscillations and having output electrodes, additional amplifying tubes coupling said output electrodes of said first amplifying tube to a utilization circuit, a single source of direct current potential for supplying voltages to the output electrodes of all of said tubes, means for maintaining the voltages applied to said electrodes of substantially constant value comprising non-linear resistances shunting said source, a keying tube having input electrodes connected with a source of keying potentials and having 55 output electrodes connected in shunt to the output electrodes of one of said amplifier tubes, and means for preventing excessive voltages from destroying said keying tube comprising a non-linear resistance in shunt to the output electrodes 60 thereof.

6. In a telegraph system, a source of oscillations of substantially constant frequency, means for wobbling the phase of said oscillations at tone frequency, an amplifier tube having input 65 electrodes coupled with said source of oscillations and having output electrodes, additional amplifying tubes coupling said output electrodes of said first amplifying tube to a utilization circuit, a single source of direct current potential for supplying voltages to the output electrodes of all of said tubes, means for maintaining the voltages applied to said electrodes of substantially constant value comprising non-linear resistances shunting said source of direct current potential, 70 75

6 a keying tube having input electrodes connected with a source of keying potentials and having output electrodes connected in shunt to the output electrodes of said first named amplifier tube, and means for preventing excessive voltages from destroying said keying tube comprising a non-linear resistance in shunt to the output electrodes thereof.

7. In a telegraph system, an electron discharge device having a plurality of electrodes, means for impressing wave energy on electrodes of said device, a utilization circuit coupled with electrodes of said device, a source of direct current poten-

tial, a keying tube having a controlling electrode connected with a source of keying potentials and having electrodes coupled to electrodes of said first named device and to said source of potential whereby the impedance of said first named device is controlled in accordance with the keying potentials on the controlling electrode of said second named tube, and means for protecting said second named tube from excessive voltages, comprising a non-linear resistance in shunt to a pair of electrodes thereof.

JAMES L. FINCH.
